UNITED STATES PATENT OFFICE

ERWIN H. HAMILTON, OF RIVERDALE, NEW YORK

COOLING FIN FOR INTERNAL COMBUSTION ENGINES

Application filed January 27, 1923. Serial No. 615,401.

This invention relates to improvements in the construction and formation of cooling or heat radiating fins. One use for such fins that will be referred throughout the following specification is upon air-cooled internal combustion engines.

It is one object of my invention to provide a type of cooling fin, or rather a plurality of fins that will bring the whole body of cooling air into more intimate contact with the cooling surfaces.

It is another object of my invention to provide a construction of cooling fin, which when assembled with a plurality of other cooling fins, will create a turbulent flow of air through the air passages between the cooling fins.

It is a further object of my invention to provide cooling surfaces that will cooperate with each other to create a constantly diverging but nevertheless forwardly progressing current of air passing over the cooling surfaces.

It is a still further object of my invention to provide a plurality of cooperating cooling fins with inclined surfaces, the inclination being so designed and spaced with respect to each other that a current of air flowing over the cooling surfaces will flow from one inclined surface to another surface inclined in the same general direction but spaced laterally therefrom, so that while the current of air between the cooling surfaces is caused to constantly change its path, there nevertheless is nothing located in the paths to which the air currents are directed so as to cause an abrupt arresting of the currents of air, but rather a steady forward progression in a large volume as if the inclined surfaces were not in fact present.

Other and further objects of my invention will be apparent from the following specification taken in conjunction with the accompanying drawings, wherein—

Figure 1 is a fragmentary view of a cyl-

inder provided with continuous, one-piece cooling fin of my improved construction;

Fig. 2 is a fragmentary view of a surface to be cooled equipped with straight cooling fins surrounded by a shroud or contacting 50 cooling surface of my improved construction;

Fig. 3 is a fragmentary view of a surface to be cooled, and cooling fins, the surface to be cooled being constructed as the outer cooling surface or shroud of Fig. 2;

Fig. 4 is a modified form of cooling fins provided with indentations of a conformation to produce the above-referred to effects, and

Fig. 5 is a further modified form of cooling 60 fin arrangement providing the type of co-acting inclined surfaces referred to above.

Referring to Fig. 1, the cylinder 2 is provided with a plurality of cooling fins 1, spaced laterally from each other.

The cooling fins 1 are provided with a plurality of corrugations or indentations 4. These corrugations or indentations are not of the substantially semi-circular shape, but are each provided with gradually sloping surfaces 3 and 5, which terminate in the base or apex of the indentation on respective sides thereof.

These indentations with their gradually sloping surfaces 3 and 5 are of such a length, 75 and the cooling fins are spaced laterally from each other so that a current of air encountering the inclined surface 3 rolls or flows along that surface which directs the current of air diagonally and progressively forwardly toward the next adjacent cooling fin. The current of air when it engages the next adjacent cooling fin 4 does not meet an abrupt surface that is more or less at right angles to its path, but instead the current of air passes over the head of the particular indentation 4 and directly onto and along the surface 5 of that indentation. The current of air will flow along the surface 5 into the indentation connected thereto, and 85 90

along its surface corresponding to the surface 3 referred to above, which surface 3 will direct the current of air back toward the fin from which it first came, but diagonally and 5 in a forwardly progressing direction, where the current of air will engage another inclined surface that is inclined in the direction of its flow.

10 The above described cycle is occurring between each pair of fins and along the surfaces 3 and 5 of the indentation spaced laterally and diagonally from each other.

15 Referring now to Fig. 2, a cooling surface 22 is shown as provided with a plurality of laterally spaced cooling fins 21 that are here shown as the usual and customary straight surface cooling fins. These are surrounded and bound by a cooling fin or surface or shroud 23, which cooling surface is provided 20 with a plurality of indentations 24 each respectively provided with inclined surfaces 26 and 27, corresponding respectively to the surfaces 3 and 5 described above in connection with Fig. 1.

25 In this form of the invention, the air current will be directed from a surface 27 diagonally across to the surface 22 to be cooled, and be deflected from that surface diagonally back to the fin or shroud 23, where it will 30 engage a surface 26, flow into and out of an indentation 24 in the same manner as described above in connection with Fig. 1, without an abrupt interruption of the air current which will result in eddy currents in the indentations and thus interfere with the full 35 cooling effect of the particular volume of air passing between the cooling fins.

40 Referring to Fig. 3, the reverse of the arrangement of Fig. 2 is shown. Here the surface to be cooled 32, is provided with a plurality of cooling fins 31 that are surrounded by a shroud 33, the cooling fins and shroud 33 being shown as straight, smooth surfaces. 45 The outer surface of the surface to be cooled is provided with a plurality of indentations 34 each having an inclined surface 36 and 37 respectively of the same shape and adapted to function in the same manner as described 50 in connection with Fig. 2.

55 Referring to Fig. 4, there is shown a modified construction of cooling fin. The cylinder 42 is provided with a plurality of spaced cooling fins 41. There is struck-up or pressed in each fin a plurality of baffle sections 45. Each section resembles in shape one half section of a cone, and the two adjacent baffles are arranged with the bases of the cone sections toward each other. With this form and arrangement of baffles the air currents are caused to be deflected from one cooling fin to another and there is no danger of causing an abrupt arresting of the forwardly moving air currents while the air currents are nevertheless put in a state of commotion so as to cause

the full volume of air to engage the surfaces of the cooling fins.

60 In Fig. 5 there is shown a still further modified arrangement of cooling fins and baffles. Herein, the wall 52 to be cooled is provided 70 with a plurality of cooling fins 51 which are straight sided members spaced apart. Mounted in the channels between the fins are a plurality of baffles 56 which are oblong shaped and arranged angularly with one baffle inclined in one direction and the next adjacent baffle inclined in a direction substantially at right angles to the first baffle, and so on alternately along the channels. However 75 it will be noted that the baffles are not arranged vertically and horizontally but angularly so that the air currents are directed back and forth from fin to fin but are always free to progress forwardly through the channel unimpeded but in fact directed by the angularly arranged surfaces of the baffles.

80 From the foregoing it will be seen that I have provided a number of arrangements or constructions of cooling fins and/or associated baffles that accomplish almost equally well the major purpose of this invention of placing the air currents passing over a surface to be cooled in substantial commotion so as to bring the mass of air in contact with the surfaces and yet aid and abet the movement of the turbulent air through the channels between the cooling fins by proper direction and guidance thereof, while at the same time increasing the area of the cooling surfaces.

85 It will be understood that various modifications and arrangement of parts may be made within the spirit and scope of my invention but such modifications are intended to be covered by the appended claims.

90 I claim:

1. The combination with a cylinder adapted to have currents of air circulating thereover, of a plurality of heat radiating devices on said cylinder having angularly disposed surfaces adapted to direct the currents of air from one cooling surface to another, the surfaces being disposed with respect to each other so that the currents of air encounter surfaces inclined in the direction of the movement of the air current whereby the full volume of air engages said cylinder and heat radiating devices.

110 2. The combination with a cylinder and a plurality of serpentine formed heat radiating fins thereon, the indentations in each fin being so shaped and disposed that air moving therealong is deflected from one indentation toward an indentation in the next adjacent fin so disposed that the volume of air engages the last mentioned indentation and flows thereover in a continuous forwardly progressing movement.

120 3. The combination with a cylinder to be cooled by air currents flowing thereover, of

means for assisting in such cooling and governing the direction of flow of said air currents, some of said means presenting inclined surfaces to cause the air currents to flow from one surface to another, the direction of inclination being in the direction to cause continuous forward progression of the air currents over the cylinder.

4. The combination with a cylinder adapted to be cooled by air currents passing therover, of a plurality of heat radiating devices mounted thereon and arranged with inclined surfaces over which air currents may pass, inclined surfaces that are vertically spaced apart of different and adjacent radiating devices being in the same plane.
